UNITED STATES PATENT OFFICE.

SIDNEY McL. AUGUSTINBAUGH, OF CHAMBERSBURG, PENNSYLVANIA.

FASTENING DEVICE FOR FILM-REELS.

1,048,270.

Specification of Letters Patent. Patented Dec. 24, 1912.

Application filed August 16, 1911. Serial No. 414,303.

To all whom it may concern:

Be it known that I, SIDNEY McL. AUGUSTINBAUGH, a citizen of the United States, and a resident of Chambersburg, county of Franklin, and State of Pennsylvania, have invented a certain new and useful Improvement in Fastening Devices for Film-Reels, of which the following is a full, clear, and exact specification.

10 This invention relates to a class of devices adapted to detachably hold a moving picture-film upon a reel.

My invention has for its object primarily to provide a fastening device designed to be 15 employed to permit a moving-picture film to be applied or disconnected with facility to a reel used with kinetoscopes, and which is adapted to allow the usual or any preferred form of end plates to be used in connection therewith.

A further object of the invention is to provide one or a number of yielding gripping elements or fingers for detachably holding the picture-film upon the hub of the reel 25 and which are formed so as to be especially durable and efficient in order to permit the film to be wound and rewound upon the reel with frequency, thus overcoming the objections to the methods in ordinary use where- 30 in the attaching means soon become damaged and cause delay and annoyance.

A practical embodiment of the invention is represented in the accompanying drawing forming a part of this specification in 35 which similar characters of reference indicate corresponding parts in all the views, the said invention being more fully described hereinafter and then pointed out in the appended claims.

40 In the drawing, Figure 1 is a side elevation of one form of my improved fastening device for film-reels with one of the end plates removed from the hub. Fig. 2 is a vertical section through the reel, and Fig. 3 45 is a perspective view of the fastening device.

The fastening device 10 is adapted to be applied upon the usual or any preferred form of hub or axle 11 having a groove or notch, as 12 and 13, provided at the peripheral edge of the face of each end thereof.

Upon the ends of the hub 11 is attached in any suitable manner the plates or disks 14 and 15 of the reel, and each of said disks has an opening 16 through which the hand 55 of a person is passed when applying a picture-film upon the reel.

The fastening device 10 has a body portion 17 which is preferably in the form of a strip or plate of metal or other material, and said body portion is adapted to be disposed transversely upon the circumferential face of the hub 11. The transverse plate 17 may be of the same length as the hub 11, and upon each end of said plate may be provided an eye or lug 18 and 19. The eyes or lugs 18 and 19 serve as means to permit the fastening device to be secured to the hub 11 and are disposed at a right angle to the plate 17 so as to be adapted to be guided into the notches 12 and 13 respectively of the hub, in order to permit a pin or screw to be forced therethrough and into the ends of said hub. Midway of the plate 17 and at a right angle thereto are provided two oppositely disposed gripping elements or fingers 20 and 21. The gripping elements or fingers 20 and 21 are curved to conform with the curvature of the hub 11, and each of said fingers may be of a length to extend sufficiently around said hub whereby the ends 80 thereof are spaced apart a suitable distance. I prefer to make each of the fingers 20 and 21 of spring metal so as to yieldingly engage the surface of the hub 11, though said fingers may be made of any other desired material, 85 and the free end of one or both of the fingers may be curved or struck upwardly, as at 22, whereby the end of a picture-film, as 23, may be readily inserted between one of the fingers and the hub, in order to permit the 90 film to be firmly held so as to be properly wound upon the reel.

In the foregoing description I have embodied the preferred form of my invention, but I do not wish to be understood as limiting myself thereto, as I am aware that modifications may be made therein without departing from the principle or sacrificing any of the advantages of this invention, therefore I reserve to myself the right to 100 make such changes as fairly fall within the scope thereof.

Having thus described my invention, I claim as new and desire to secure by Letters Patent:

105 In a device of the character described, the combination with a reel having a hub, said hub having a recess in each face thereof, of a frictional gripping device comprising a plate, a lug on each end of said plate having an eye therin, said lugs adapted to be received into the recesses of the hub so as to

permit a fastening element to be passed through the eyes whereby the plate may be attached to the hub, and a finger of spring material provided upon each side of the plate midway the ends thereof and disposed at right angles thereto, each finger being curved to conform to the curvature of the hub and having the free end thereof curved upwardly whereby the end of a film may be

readily inserted between one of the fingers 10 and the hub.

This specification signed and witnessed this fifteenth day of August A. D. 1911.

SIDNEY McL. AUGHINBAUGH.
